UNITED STATES PATENT OFFICE.

WILBERFORCE BEECHER HAMMOND, OF BOSTON, MASSACHUSETTS.

AUTOMATIC SPRINKLER.

1,177,182.

Specification of Letters Patent.

Patented Mar. 28, 1916.

Application filed April 19, 1915. Serial No. 22,294.

To all whom it may concern:

Be it known that I, WILBERFORCE BEECHER HAMMOND, a citizen of the United States, and resident of Boston, in the county of 5 Suffolk and State of Massachusetts, have invented new and useful Improvements in Automatic Sprinklers, of which the following is a specification.

My invention relates to automatic fire-protection sprinklers, and consists in improvements by which the heat-sensitive member which is a characteristic of all automatic sprinklers, is rendered insensitive to heat communicated from within the sprinkler head or the piping system on which it is mounted, while remaining at least as sensitive as heretofore, to heat communicated from the air surrounding the protective system.

Generally defined, my invention consists in the provision of a superficially extensive heat diffuser intimately attached to or incorporated with, the heat-sensitive member of the sprinkler head, the function of which is to dissipate heat conducted to said sensitive member from within the sprinkler system, while external conditions remain normal and to collect heat and transmit it to the sensitive member, whenever the external conditions are modified by a marked rise in temperature, as in case of fire.

This invention is peculiarly adapted to automatic sprinklers mounted on a hot water heating system.

In the drawings hereto annexed which illustrate my invention, Figure 1 is an elevation, partly in section, of a sprinkler head; Fig. 2 is a side elevation of the heat-sensitive member; and Fig. 3 is a plan view of the same.

The sprinkler head selected for purposes of illustration is one of the Evans type, in which the water valve is normally held closed by a toggle lever system, retained by 45 the sensitive member, which in this type is a link, held under tension. My improvements herein described are applied to the sensitive member itself, and may be adapted to the heat-sensitive members of other types 50 of sprinkler.

In the drawings, (Fig. 1), H represents the sprinkler head framework, V the water valve, and T, T', the toggle-pair, terminating in lever arms L, L', which are held nor-

mally under restraint by the heat-sensitive 55 fusible, or partly fusible, link F.

In order to render the link F (which is representative of heat-sensitive members of all accepted types of sprinklers) insensitive or indifferent to heat transmitted by conduction through the lever arms L, L', I provide superficially extensive heat-diffusing means, specifically represented by the coil of wire W, which is conductively joined to the link F by solder S. Preferably the wire W will 60 be black-japanned, to enhance its heat radiating capacity. Preferably also, I form the open coil of wire W in turns of graded amplitude, so that the turns will not stand immediately one over another, but will be so 65 distributed as to allow air to circulate through and over them to best advantage. The heat diffuser W, under normal conditions therefore dissipates heat received by conduction from the lever arms L, L', and 70 75 is capable of dispersing heat at a rate far in excess of the conduction-rate. The free air circulation around the heat-diffuser promotes this operation.

When the emergency of fire in the protected region calls for action of the sprinkler, the functional properties of the heat diffuser W render the sensitive member F more susceptible. The provisions for extensive superficial contact with circulating air 80 which under normal conditions enable the heat diffuser to disperse heat conducted to the sensitive member, render it effective as a heat collector when heat is convectively 85 communicated by the surrounding air. The 90 resultant novel utility lies in maintaining the sensitive member F in a condition of indifference to heat internal in the water system, and at the same time in a condition of hypersensitiveness to heat external to the water 95 system. Although the link F may be of any approved form, in the example shown in the drawings it consists of a pair of overlapping plates held together under normal conditions by a readily fusible solder. In case of 100 fire the solder melts and allows the two plates to pull apart releasing the toggle-lever members. In order to insure that the coil W shall not bind the two plates and prevent their ready separation, one plate of the pair 105 is made a little narrower than the other, as best shown in Fig. 2, and the coil W is soldered to the edges of only the broader

2
plate. This leaves the narrower plate of the pair free to pull out through the end of the coil W.

What I claim and desire to secure by Letters Patent is:

1. The combination, in an automatic sprinkler, of the characteristic heat-sensitive member, and a superficially extensive conductive member, secured in heat conductive relationship directly to the heat-sensitive member.
2. The combination, in an automatic sprinkler, of the characteristic heat-sensitive member, and a convoluted wire, secured in heat conductive relationship directly to the heat-sensitive member.
3. The combination, in an automatic sprinkler, of the characteristic heat-sensitive member, and a wire, bent into convolutions of varying amplitude, secured in heat conductive relationship directly to the heat-sensitive member.
4. The combination, in an automatic

sprinkler, of a heat-sensitive member comprising a pair of elements secured together by fusible solder, and a superficially extensive conductive member, secured to one only of said pair of elements.

5. The combination, in an automatic sprinkler, of a heat-sensitive member comprising a pair of elements secured together by fusible solder, and a convoluted wire secured to one only of said pair of elements.

6. The combination, in an automatic sprinkler, of a heat-sensitive member comprising a pair of plates, one broader than the other, secured together by fusible solder, and a coil of wire secured only to the edges of the broader of said plates.

Signed by me at Boston, Massachusetts, this third day of April, 1915.

WILBERFORCE BEECHER HAMMOND.
